SHIELDING SHOE FOR FILTERS

Nils Gustav Leffler, Sundsvall, Sweden

Application August 9, 1946, Serial No. 689,314
In Sweden August 14, 1945

23 Claims. (Cl. 210—199)

1

The present invention relates to filters of the type embodying a movable perforated filter member adapted to pick up on its one side solids from a suspension and to discharge suspension liquid at its other side after passage through the openings thereof under the influence of a differential pressure between said sides. Such a filter is usually, but not always, formed as a rotary cylindrical drum the peripheral surface of which is perforated and provided with a fine mesh wire fabric for picking up the solids of the suspension in which the drum is partially submerged, and wherein the differential pressure is produced either by evacuating the interior of the drum or subjecting the outer surface thereof to a super-atmospheric pressure. The invention is especially adapted for embodiment in rotary drum filters for picking up solids, such as fibers, powders and granules, from suspensions in liquids and is more particularly concerned with an improved construction of a shielding shoe for such filters. It is a further development of the invention I have disclosed in my previous application Ser. No. 652,464, filed March 6, 1946, for "Filter."

As in the case of my previous invention above referred to, the present invention has also for its primary object to provide a shield shoe of the kind defined which will secure a sufficiently good sealing around that portion of the wire fabric where the taking off takes place. It is another object so to construct the shoe that it will in a high degree be independent of variations in said difference in pressure. A further object is to provide a sealing shoe which will close off the take off portion effectively in filter drums even if the drum is not perfectly circular. An object of the present invention in addition to the aforesaid objects is to provide a sealing shoe the frictional wear of which against the moving filter member will be immaterial.

The invention will now be described more in detail with reference to the accompanying drawings illustrating various embodiments by which the invention may be realized in connection with vacuum drums for paper making but it is to be understood that the invention is not limited to the features so shown but has to be taken in its broadest scope.

In the drawings, wherein like reference numerals indicate like parts throughout the several views, Fig. 1 is a cross sectional side elevation of the taking-off portion of a filter drum of the cell-free type and the shielding shoe according to the invention and Fig. 2 is a frag-

2

mentary front elevation of the shoe of Fig. 1 looking from the right in the latter figure, the drum being removed and a portion of the shoe being broken away to show details of construction. Fig. 3 is a fragmentary cross section of the shoe along the line 3—3 in Fig. 1. Fig. 4 is a sectional view similar to Fig. 3 showing an alternative connection between the stationary and the movable parts of the shoe. Figs. 5 to 7 show in the same way as Figs. 1 to 3, respectively, another embodiment of the invention and Fig. 8 is a fragmentary cross section showing an alternative means for securing the movable part of the shoe to the stationary part. Figs. 9 and 10 show in section and from the outer side, respectively, one embodiment, and Fig. 11 shows in section another embodiment, of certain roll supporting means according to the invention. Figs. 12 to 14 show in the same way as Figs. 1 to 3, respectively, a third embodiment of the shoe according to the invention. Fig. 15 is a fragmentary cross-sectional view similar to those of Figs. 3, 4, 7, 8, 14 and shows a flexible ribbon for securing longitudinal sealing between the stationary and the movable members of the shoe. In these views certain of the parts have been broken away or omitted, and others have been shown in full instead of in section, in order to simplify illustration of the invention.

Referring first to Figs. 1 to 3, the filter drum comprises a cylindric perforated support 1 on the outer surface of which the wire mesh fabric, not shown in the drawings, is applied for taking up the solids suspended in a slurry of, for instance, cellulose fibers to form therefrom the fiber cake 4. The support or filter member 1 is mounted in the disc-like ends 2 being rotatably journaled in bearings not shown in the drawings. At the outside of the filtering member the doctor 3 is arranged in the usual way for removing the cake 4 deposited on the filter. The drum is considered to rotate in the direction of the arrow at the upper end of Fig. 1 and to be submerged in the fiber slurry 5.

At the place of discharge of the filter, that is at the doctor knife and downwards to the level of the slurry 5, the shielding shoe is applied. The function of the shoe being to seal off the communication between the interior of the drum and the outer atmosphere, partly to facilitate the removal of the cake and partly to prevent air from getting access to the interior of the drum through the portion of the filter member made naked at the doctor, the shoe extends beyond this place of discharge at

either side in the peripheral direction. The shoe is in the axial direction substantially coextensive with the filtering member or in other words with the foraminous portion thereof. In the drawings the shoe is submerged in the filtrate below the level 6 but this is not at all necessary for its satisfactory function. In filter drums where the filtrate is discharged at a low point in the drum the level of the filtrate is preferably below the lowermost portion of the shoe.

The sealing member of the shoe comprises the endless band 7 of an elastic or flexible material, such as rubber or thin steel plate. The stationary member and the band are so shaped and arranged that when pressure medium is supplied to a liquid-tight chamber formed between said members through the conduit 21 the hydraulic pressure prevailing in this chamber presses the band 7 against the filter member, thereby effectively closing off all the openings in that part of the foraminous portion of the filter member underlaid by the band. In the embodiment shown in Figs. 1 to 3 the band 7 is pressed against sliding surfaces 22 on the stationary member 14 as well as against the filter member. In order to minimize the friction against the sliding surface 22 grooves (similar to groove 28 in Fig. 3) may be made in said surface and be connected with the pressure medium of the chamber through channels in the material of the stationary member. Once the band has been pressed against the sliding surfaces 22 and the filter member it will travel with the filter member in sealing engagement with said sliding surfaces. Means for keeping the band in approximate working position—for instance a bar or perforated pipe near the upper sliding surface 22—ought to be provided so that the band will be put in sealing position upon admitting pressure liquid to the pressure chamber, as through said pipe.

In order, however, to insure proper functioning of the band in the shoe the band may be caused to run over guide rolls 8 and 9 and a jockey roll 16, said rolls being journaled either directly in the stationary member 14 or in arms 11, 12 and 13, respectively, which are in turn pivoted on the pins 15, 16 and 17, respectively, secured to the stationary member. The guide rolls 8 and 9 journaled in the arms 11 and 12 may be pressed against the filter member by means of the springs 18 and 19. The jockey roll 16 is preferably pressed against the return part of the band by means of the spring 20 so as to stretch the band.

To the chamber formed by the stationary member 14 and the part of the endless belt contacting the filter member leads the conduit 21 by which the chamber can be connected to a source of pressure medium. The pressure in this pressure chamber should be higher than that outside the filter member so as to secure a perfect contact between the band and the filter member. For preventing the pressure medium from leaking into the drum the band 7 is arranged to seal against the axial surfaces 22 and the peripheral surfaces 23 of the stationary member rendering said pressure chamber substantially liquid-tight. When using as pressure medium a liquid, such as water, an effective water lubrication of the sealing surfaces will be obtained. It is then preferred always to keep the band wet on the return run from roll 9 to roll 8. Some leakage of water into the drum from the pressure chamber is not harmful to the good func-

tioning of the filter, since the vacuum in the drum will not appreciably be influenced thereby.

Sometimes the drum can be irregular, for instance as caused by different eccentricity of the cross-sections of the drum at different places along the axis. For even in this case to secure an effective sealing a portion of the band 7 is left unsupported for some length 24 between the sealing surfaces of the stationary member and the filter member (as shown in Fig. 3, the band 7 is unsupported at 24 between the peripheral surface 23 of the stationary member and the inner peripheral surface of the filter member 1 about groove 27). The embodiment shown in Fig. 4 in which the sealing surface 23 of the stationary member 14 stands at a right angle to the filter member allows a greater movement in the radial direction of the band relative to the stationary member. In this case also the band itself is preferably provided with sealing surfaces at right angles to the filter member. In order to allow the guide rolls 8 and 9 to follow the movements required by the irregular filter member the arms 11 and 12 may be equipped with spherical bearings 25 for the spindles 26 of the rolls.

By providing the peripheral sealing surfaces 23 of the stationary member 14 or the impervious border of the filter member 1 or both with peripheral grooves 27 and 28, respectively, communicating with the vacuum in the interior of the drum by channels, leak water is prevented from reaching the filter cake 4. The same effect will be attained at the upper axial sealing surface 22 if the latter is provided with a similar groove.

Although the pressure in the space between the lower sealing surface 22 and the filter member may be considered to be approximately equal to that outside the filter, that is atmospheric pressure, since the filter member is here free from fiber cake, the pressure may, however, at this place be increased by supplying pressure medium from the pressure chamber or from elsewhere to this space so as to counteract a detrimental bulging out of the band. At the upper sealing surface 22 such an arrangement is impractical since it would splash the fiber cake but an extra pressure on the outside surface of the band is not necessary here since the band moves away from the upper border of the stationary member whereas it moves toward the lower border.

Although not shown in the drawing the shoe may be secured to a stationary shaft or to spindles in the interior (centre) of the drum directly or over some support devices. By such means it is possible even during operation to regulate or move the discharge place of the filter merely by turning said shaft or spindles. The supply conduit 21 for pressure medium communicates preferably with the exterior of the drum through this shaft or spindles.

Among the advantages of this embodiment of the invention its simple design may be emphasized. All seals between the band and the filter member as well as between the band and the stationary member are obtained without extra devices. The roll spindles may be journaled in sleeves of plastics (artificial resin) and a slight wear of these sleeves is insignificant.

Figs. 5 to 11 show another embodiment of the invention. The elements having the reference numerals 1 to 21 are arranged and formed and work substantially as is described in connection

with the previous embodiment. The substantially liquidtight chamber is, however, here arranged within the opening formed by the band 7 and is limited in the peripheral direction of the drum by the guide rolls 8 and 9. The return part of the band passes therefore outside the pressure chamber.

In the radial direction of the drum the pressure chamber is limited by the wall portion 29 of the stationary member 14. Said wall portion is sealed in the peripheral direction against the rotating guide rolls 8 and 9. The sealing can be carried out in several different ways, as by means of a ribbon of leather or rubber or similar flexible material secured (in the same manner as element 57 in Fig. 15) to the inside of the wall portion 29 so as to be pressed against the rolls by the pressure medium in the pressure chamber. In the embodiment shown in the drawing, however, the wall portion 29 is provided at the upper as well as the lower end with a groove 30 carrying the sealing bar 31. The grooves 30 communicate through the holes 32 with the pressure medium in the pressure chamber rendering the bars 31 resiliently pressed against the rolls 8 and 9 so that the rolls can move against and from the filter member without jeopardizing the sealing. The bars 31 may also be pressed against the rolls by springs. The seals may be located at any place on the guide rolls between the parts of the band. The lever arms 11 and 12 may, however, preferably be secured to the stationary member in such manner as to limit to a minimum radial movement of the rolls 8 and 9 against the sealing bars 31 during their movement against or from the filter member.

The seal between the pressure chamber and the interior of the drum at the tangent lines between the rolls and the band is obtained by pressing the rolls, as by springs or weights, against the inner side of the band. The movement is then limited by the filter member.

In the axial direction of the drum the pressure chamber is limited by the sidewalls 33 (Fig. 7) of the stationary member 14 and the sealing bar 34 which is resiliently movable against the filter member in sealing relation to said sidewalls 33 and the end surfaces 35 of the rolls 8 and 9. The sealing bars 34 are hinged in brackets 38 of the stationary member by means of the arms 37 pivoted to the bars by the pins 36 and to the brackets 38 by the pins 39. By this arrangement each bar is resiliently movable against the filter member. In order to secure a good sealing between the rolls 8 and 9 and the side bars 34 also in case of irregular shape of the filter member, such as may be caused by a certain eccentricity between the cross-sections of the ends of the drum, in which case the end surfaces 35 of the rolls 8 and 9 do not move in parallel to the sidewalls 33, a packing or plate 40 of elastic material, such as rubber, is provided between each of said end surfaces 35 and the cooperating sealing bar 34. For making such a movement feasible the supporting means for the rolls 8 and 9 have to be designed accordingly. In Fig. 8 one mode of carrying out such an independent movement of the ends of the roll is illustrated. In this embodiment the arms 11 and 12 (not shown in Fig. 8) are provided with spindles fitting in the openings of the sleeves 41 secured to the stationary shafts 42 of the rolls. In case of a relative movement of the ends of the roll in the radial direction of the drum the roll moves a little about said spindles of the arms 11 and 12.

As already mentioned some leakage of water from the pressure chamber to the interior of the drum has no detrimental influence. It is therefore possible to use a labyrinth seal 43 in the rolls consisting of the grooved rotating disc-like end 35 of the roll and a stationary ring 44 designed so as to cooperate with said disc-like end 35. By this means the wear at these ends 35 of the rolls 8 and 9 is avoided and the wear 10 of the packing 40 is eliminated since the latter will seal between two elements which are stationary in relation to each other except for a slight movement to and from each other when the ends of the roll move differently in the radial 15 direction of the drum. The packing may even be fixed to the elements 34 and 44. The elasticity of the packing will then take up the relative movement between these elements. If the roll cylinder is mounted on the stationary shaft 20 42 by ball or roller bearings 66 the labyrinth seal 43 may have a very small clearance. Through a sealing device 45 outside the ball bearing 66 the latter will be protected against leak water which may come into the end portion 25 of the roll. The bearing 66 may, of course, be mounted in brackets as usual.

In the embodiment shown in Figs. 1 to 4 and in that to be described hereinbelow and shown in Figs. 12 to 15 the entire pressure difference 30 is taken up by the stationary member 14. In the embodiment according to Figs. 5 to 7, however, a given pressure will be exerted on the guide rolls 8 and 9 which is transferred to the stationary member by the springs 18 and 19. 35 The pressure of the springs is preferably somewhat greater than the pressure acting in the opposite direction on the rolls 8 and 9 by the pressure medium in the pressure chamber in order to bring about the sealing between the 40 band and the roll in the peripheral direction of the drum at the side facing the filter member.

Should, however, the vacuum in the interior of the drum decrease, possibly on account of extraneous operating conditions, the roll will be pressed harder against the band. Due to the 45 fact that the elements in question move with the same velocity and practically no frictional wear occurs, the increased pressure will not be very harmful. The variation of the pressure 50 against the band can, however, be avoided if the guide rolls 8 and 9 are journaled in a U-shaped member or fork 46 on the pins 47 as shown in Figs. 9 and 10. The fork should be sealed against the roll. The fork is in turn pivoted on the stationary member by means of the pins 48 and arms 48'. By so locating said pins 55 in the peripheral direction of the drum that the total effective pressures on the surfaces exposed to the pressure medium of the pressure chamber become equal on either side of the axis of the pins 48, the fork and the roll 8 or 9, respectively, journaled therein will substantially come into balance independently of the variations of the vacuum in the interior of the drum. By increasing the surface of the fork exposed to the 60 pressure chamber relative to that of the roll a constant pressure of the roll will be obtained against the band. The springs 18 and 19 may in that case be dispensed with.

70 Fig. 11 shows another embodiment of the pivoting of the roll in the stationary member. The sleeves 41 (Fig. 8) of the rolls 8 and 9 are journaled in the arms 49 which are in turn pivoted on the stationary member 14 on the spindles 50. The cylinder surface as well as the ends of the

rolls 8 or 9 are sealed against the stationary member. Projecting levers 49 on the arms 49 are connected through the spindles 52 and the pins 53 with the pistons or plates 51 tightly movable in openings in the stationary member 14. By this means the individual independent movement of the both ends of a roll against the filter member is perfect so that the roll will smoothly follow the irregularities of the drum.

Among the advantages of the embodiment described with reference to Figs. 5 to 11 the very low wear of the band may be mentioned. This is due to the fact that the band does not seal against stationary surfaces. The side bars 34 are, it is true, in the drawing shown to be located in close contact with the ends of the band but for sealing purposes this is not at all necessary, at least not in the space between the rolls and not even at the rolls if the latter are provided with flanges at the ends. All sealing elements between movable and stationary members can be somewhat overdimensioned and are furthermore cheap and can be readily replaced.

In Figs. 12 to 15 a third embodiment is shown. The elements having the reference numerals 1 to 21 and 29 are arranged and formed and work essentially in the same way as has been described in connection with the previous embodiments with respect to elements having same numerals. The substantially liquidtight pressure chamber is also in this case located within the opening formed by the parts of the band 7. The sealing bars 54 at the upper and lower ends of the wall portion 29 of the stationary member are, however, contrary to the bars 34 of the previous embodiment, not placed in contact with the rolls 8 and 9 but the shoe has instead been designed so that the bars 54 seal directly against the inner surface of the band 7 near the rolls 8 and 9. By this means sealing against the cylindric surface and the end of the roll is avoided. In order to reduce the wear of the band the sealing bars may be replaced by small diameter rolls rotating in contact with the band and being sealed against the stationary member. The sealing side bars 55 limit together with the side wall 56 of the stationary member 14 the extension of the pressure chamber in the axial direction of the drum. The bars 55 are resiliently movable against the inner surface of the drum in the same way as the sealing bar 34 of the preceding embodiment. In Fig. 15 another embodiment of the sealing in the axial direction has been illustrated. A flexible sealing ribbon 57 made of, for instance, leather or rubber is here secured to the sidewall 56 of the stationary member 14 and is pressed against the band 7 or against the end 2 of the filter member outside the band by the pressure medium.

Among the advantages of the last described embodiment the simple execution of the seals may be emphasized.

Since, for the contemplated function of the shoe, sealing is required against the filter member only around the circumference of the contacting portion of the shoe, the band according to the present invention may be replaced by one comparatively narrow belt at each end of the rolls. The rolls should then be provided with a suitable sealing means, such as a coating or cover of rubber, between said belts and in contact with the filter member. The sealing member being now open towards the filter member a vaporous pressure medium must be used in the pressure chamber formed in the shoe. In

order to bring about the sealing required between the belts and the filter member each belt has to be provided with a pressing device along its inside surface between the rolls. For this purpose boxes may be used having slots in the walls facing the belts and inlets for a gaseous or liquid pressure medium to work on the belts through said slots.

It is, of course, possible to a certain extent to combine the various sealing means described in connection with the different embodiments. At places where only minor reciprocating movements occur the sealing elements may be fixed to the members moving in relation to each other, the elasticity of the sealing means then rendering the movement possible.

The invention has now been described with reference to some different embodiments but it is to be understood that it is not limited to these embodiments or the special details shown and described. In addition to various combinations of the embodiments also quite different embodiments may come into question. Thus two or more shoes of the present kind may be arranged one after the other and be provided with a common case kept in liquidtight relation to the filter member. Furthermore one or more of the rolls disclosed may be driven by special driving means, such as chains or belts, which may be driven by the shaft in the centre of the drum. In case the drum is arranged for interior feed and the shielding shoe therefore is provided on the outer side of the drum, the driving of the rolls can, of course, be easily performed. Employed with cell filters in which the cells open at the one or both ends of the drum the shoe of the invention will be placed over an appropriate number of such cell openings at the end of ends of the drum. Although particularly described in connection with filter drums submerged in a suspension of fiber it is to be understood that the invention can be employed equally well in conjunction with other types of picking up machines for suspended solids where these are picked up on a foraminous member by the action of a pressure difference between opposite sides of the foraminous member.

As used in the specification and claims hereof, the words "seal" and "sealing" are not intended to apply solely to conditions in which a perfect seal is effected, because frictional seals are seldom, if ever, absolutely airtight or watertight. Instead, these words should be interpreted to mean that the leakage of air, water or other fluid is inhibited to the maximum degree practicable in structures of the character described, and that where the "seal" is made by frictional engagement between relatively movable members, a limited amount of leakage may exist without seriously impairing the utility of the invention.

What is claimed is:

1. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a rigid stationary shoe member and a movable sealing shoe member, said movable sealing shoe member comprising an endless flexible member of impervious material adapted to contact and seal a portion of said perforated filter member and to move revolvingly therewith, means for supporting said endless flexible member for move-

ment relative to said stationary shoe member and with said perforated filter member, said stationary shoe member including walls forming a chamber having an open side facing said perforated filter member, means including said endless flexible member for closing the open side of said chamber and rendering the latter substantially liquidtight, and means for supplying fluid under pressure to said chamber for pressing said endless flexible member into contact with said perforated member.

2. A shielding shoe as claimed in claim 1 wherein at least one end of said stationary shoe member is provided with a supporting surface over which said endless member passes in sliding engagement, and which includes means for maintaining said endless member in approximate working position adjacent said surface.

3. A shielding shoe as claimed in claim 2 including grooves in said supporting surface communicating with said chamber.

4. A shielding shoe as claimed in claim 1 including at least one roll about which said endless member is movable, said roll being disposed adjacent the rear end of said stationary shoe member as viewed in the direction of movement of said endless member.

5. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a rigid stationary shoe member and a movable sealing shoe member, said movable sealing shoe member comprising two rolls disposed one at each end of said stationary shoe member and an endless flexible band of impervious material movable about said two rolls and adapted to contact and seal a portion of said perforated filter member and to move revolvably therewith, means for rotatably supporting said rolls from said stationary shoe member, said means being so constructed and arranged that at least one of said rolls is movable relatively to said stationary shoe member toward and away from said perforated filter member, said stationary shoe member including walls forming a chamber having an open side facing said perforated filter member, means including said endless flexible band for closing the open side of said chamber and rendering the latter substantially liquidtight, and means for supplying fluid under pressure to said chamber for pressing said endless flexible band into contact with said perforated filter member.

6. A shielding shoe as claimed in claim 5 wherein said roll supporting means includes an arm pivotally mounted on said stationary shoe member, and means for rotatably journaling said movable roll in said arm.

7. A shielding shoe as claimed in claim 5 including at least one additional roll in contact with said endless band, adjustable means for rotatably supporting said roll from said stationary shoe member, and yieldable means for urging said roll in such direction as to stretch said band.

8. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a rigid stationary shoe member, and a sealing shoe

member at least a part of which is movable relative to said stationary shoe member, said sealing shoe member comprising a pair of rolls, one at each end of said stationary member, and an endless flexible member of impervious material movable about said rolls, said endless member having a contacting portion movable along with and, at least for the greater portion of its length, in contact with said movable filter member and 10 a return portion, said stationary shoe member including walls forming a chamber having an open side facing said movable filter member, and means including the contacting portion of said endless member for closing the open side of said chamber and rendering the latter substantially liquidtight.

9. A shielding shoe as claimed in claim 8 wherein the return portion of said endless flexible member is within said chamber.

10. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a rigid stationary shoe member, a pair of rolls substantially parallel to one another, and an endless flexible member of impervious material movable about said rolls, said stationary shoe member including a wall portion spaced from and generally parallel to said movable filter member, located between said rolls and in substantially liquidtight contact therewith, said endless member having a portion between said rolls generally parallel to said wall portion movable along with and, at least for the greater portion of its length, in contact with said movable filter element, and means including, said wall portion of 40 the stationary shoe member, said rolls and the filter contacting portion of said endless member forming the enclosure of a substantially liquid-tight chamber.

11. A sealing shoe as claimed in claim 10 including a pair of sealing bars extending between said rolls at the ends thereof and yieldably movable toward said movable filter member, said sealing bars having substantially liquidtight contact with said rolls and said stationary shoe member.

12. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a rigid stationary shoe member, an endless flexible member of impervious material revolvably movable relative to said stationary shoe member and having a portion spaced from said stationary shoe member and adapted to contact a portion of said movable filter member, sealing means between said stationary shoe member and the inside surface of said endless member at the ends of said stationary shoe member in the direction of movement of said endless member, means including said stationary shoe member and the portion of said endless member between said sealing means forming the enclosure of a substantially liquidtight chamber, and a conduit leading to said chamber.

13. A shielding shoe as claimed in claim 1 including at least one roll rotatably supported by said stationary shoe member and about which

said endless flexible member is movable, the ends of said roll being independently movable toward and away from said filter member.

14. A shielding shoe for filters of the type embodying a filter member comprising a perforated portion surrounded by an impervious frame portion and being adapted to pick up on its one side solids from a suspension and to discharge suspension liquid at its other side after passage through the openings thereof under the influence of a differential pressure between said sides, said shoe comprising a rigid stationary shoe member having a side wall generally parallel to said filter member, end walls perpendicular to said side wall and an open side facing said filter member, an endless band of impervious material movable relative to said stationary shoe member and closing the side thereof facing said filter member except for relatively narrow spaces between the end walls of said stationary shoe member and the edges of said endless band, portions of said endless band adjacent its edges being in contact with the impervious frame portion of said filter member, and means for sealing said spaces, said sealing means being so constructed and arranged as to maintain the seal while permitting a limited movement of said band toward and away from the side wall of said stationary shoe member.

15. A sealing shoe as claimed in claim 14 wherein said sealing means comprises a sealing bar movable in contact with said stationary shoe member into frictional engagement with said impervious frame portion.

16. A shielding shoe as claimed in claim 15 wherein said sealing bar is provided with a surface perpendicular to said band and in sliding engagement with the edge thereof.

17. A shielding shoe as claimed in claim 14 wherein said sealing means comprises a flexible sealing ribbon fixed to each end wall of said stationary shoe member and so constructed and arranged that one of its surfaces is in contact with the portion of said endless band adjacent said end wall.

18. A sealing shoe as claimed in claim 14 wherein said sealing means comprises a surface on said stationary shoe member parallel to and in sliding contact with the marginal portion of said band, said band having an unsupported portion between the portions thereof in contact with said impervious frame portion and said surface.

19. A shielding shoe as claimed in claim 18 wherein at least one of the portions of said impervious frame portion and said surface in contact with said endless band is provided with a groove communicating with a source of vacuum.

20. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a stationary shoe member and an endless flexible member of impervious material, said end-

less member having a contacting portion movable along with and, at least for the greatest portion of its length, in contact with said movable filter member and a return portion; said stationary shoe member including walls forming a chamber having an open side facing said movable filter member, means including the portion of said endless member in contact with said movable filter member for closing the open side of said chamber and rendering the latter substantially liquidtight, means for supplying a fluid under pressure to said chamber, and means outside said chamber for supplying liquid under pressure to the contacting portion of said endless member.

21. A shielding shoe as claimed in claim 1 including at least one feeder roll about which said endless flexible member is movable.

22. A shielding shoe as claimed in claim 1 including a flexible sealing ribbon fixed to said stationary shoe member and so constructed and arranged that one of its sides is maintained in sealing contact with said endless flexible member by the pressure in said chamber.

23. A shielding shoe for filters of the type embodying a filter member comprising a perforated portion surrounded by an impervious frame portion and being adapted to pick up on its one side solids from a suspension and to discharge suspension liquid at its other side after passage through the openings thereof under the influence of a differential pressure between said sides, said shoe comprising a rigid stationary shoe member having a side wall generally parallel to said filter member and end walls perpendicular to said side wall forming a chamber having an open side facing said filter member, an endless band of impervious material movable relative to said stationary shoe member and having portions adjacent its edges in contact with the impervious frame portion of said filter member, said band and impervious frame portion closing the open side of said chamber except for relatively narrow spaces between the end walls of said stationary shoe member and said impervious frame portion, and means for sealing said spaces to render said chamber substantially liquidtight, said means being so constructed and arranged as to maintain the seal while permitting rotary movement of said impervious frame portion relative to said stationary shoe member.

NILS GUSTAV LEFFLER.
